UNITED STATES PATENT OFFICE.

WARREN V. JOHNSON AND ROBERT C. KEPNER, OF BLOOMSBURG, PENNSYLVANIA, AS
SIGNORS TO AMERICAN CAR AND FOUNDRY COMPANY, OF NEW YORK, N. Y., A
CORPORATION OF NEW JERSEY.

MINE CAR.

Application filed December 23, 1924. Serial No. 757,659.

Reference is had to the accompanying drawings which illustrate the preferred form of the invention; though it is to be understood that the invention is not limited to the exact details of construction shown and described, as it is obvious that various modifications thereof within the scope of the claims will occur to persons skilled in the art.

In said drawings:

Fig. 1 is a view showing the improved mine car in side elevation;

Fig. 2 is a view showing the mine car in end elevation;

Fig. 3 is a top plan view of the improved mine car;

Fig. 4 is a fragmentary transverse sectional view taken along the line 4—4 of Fig. 1;

Fig. 5 is a fragmentary sectional view taken along the line 5—5 of Fig. 1;

Fig. 6 is a fragmentary view in elevation showing the coupling pin and latch at one end of the mine car, and

Fig. 7 is a sectional view taken on the line 7—7 of Fig. 1.

An object of this invention is to provide a mine car having an improved body portion including an intermediate section formed of longitudinally disposed floor boards and side sections formed of sheet metal and connected with the intermediate section in an improved manner.

Another object of the invention is to so connect the side sections with the intermediate section that they will be very securely held in place and firmly braced against downward movement.

Another object of the invention is to so construct the side sections that portions of these sections intermediate the length of the car may be arched upwardly and provide external pockets open at their lower and outer sides and adapted to receive the upper portions of the wheels of the car.

Another object of the invention is to so form these pockets that brake structure may be suspended intermediate the ends of the pockets and between the wheels of the car.

This improved mine car is provided with a body portion having side walls 1, end walls 2 and a bottom indicated in general by the numeral 3. This bottom 3 is provided with an intermediate section formed of

longitudinally disposed floor boards 4 and side sections 5 which are formed of sheet metal. The floor boards 4 are of greater length than the body portion and have their end portions extending beyond the end walls and covered by metal jackets or bumpers 6 which straddle the extended ends of the boards 4, as shown in Fig. 1. Fasteners 7 pass through the boards 4 and upper and lower flanges of the bumpers so that the bumpers will be securely held in place. The extended ends of the center board 4 and the flanges of the bumpers are also provided with openings to receive the coupling pins 8 which pass through the eyes at the ends of the draw bar 9. This draw bar 9 extends longitudinally of the car intermediate the width of the center board 4 and has its end portions extended upwardly and then outwardly through the end walls in spaced relation above the extended ends of the center board. The pins 8 are adapted to pass through mine car couplers of a conventional construction and may be secured against accidental upward movement when in place. At one end of the car there has been shown a latch for retaining the coupling pin in place and this latch is illustrated in Fig. 6. Referring to this figure and to Fig. 1, it will be seen that the latch 10 is in the form of a strip which is pivotally connected with the end wall by means of a pin or bolt 11 which passes through the end wall and through a bracket 12. The lower end portion of the latch forming strip is bent to provide an arm 13 which extends outwardly from the end wall of the car body and is of such length that it may be positioned between the collar 14 and head 15 of the pin. Therefore the pin will be securely held in place until the latch is swung out of an operative position.

Each of the side sections 5 of the body is formed of metallic plates 16 which have their inner side portions extending in overlapping relation to the intermediate section, as shown in Figs. 4 and 5, and have their outer side portions bent upwardly to provide flanges 17 which are secured to the lower edge portions of the side walls 1 by means of rivets 18. The metallic plates which form the wheel hood portions of the side sections intermediate the length of the car body are stamped to provide bowed por-

tions 19 which extend upwardly into the car body and provide external pockets 20 which are open at their outer and lower sides. Of course the intermediate portions of the 5 side walls have their lower edge portions removed at this point to correspond to the pocket and permit ready access to the wheels so that the flanges of the plates forming the intermediate or wheel hood portions of the 10 side sections may be secured to the side walls, as shown in Fig. 5. In order to firmly connect the side floor sections with the intermediate floor section there have been provided Z-bars 21 which extend along 15 the side edge faces of the intermediate section and have their upper flanges 22 secured to the under faces of the side sections by rivets 23 and their lower flanges 24 extending beneath the side portions of the intermediate section and secured by bolts or 20 other suitable fasteners 25 which extend through the intermediate section and through the overlapped inner side portions of the side sections. This is clearly shown 25 in Figs. 4 and 5 and referring to these figures, it will be seen that the side sections will be very securely attached to the intermediate section. There has also been provided yokes 26 which have their bridge portions 30 extending transversely beneath the body and their arms 27 extending upwardly along the outer faces of the side walls and constituting posts which will be secured to the side walls by the rivets 28. The intermediate 35 portions of the bridge portions of these yokes are secured to the intermediate floor sections by bolts or other fasteners 29 and the end portions of these bridge portions are bent at an upward incline, as shown at 40 30, and then extended outwardly along the under faces of the side sections of the flooring and secured by rivets 31. The floor boards and metal plates forming the flooring of this improved mine car body will therefore be very firmly connected with each other 45 and braced against movement out of the desired position. The upper edge portions of the side walls are bent outwardly and downwardly to provide depending stiffening flanges 32 which overlap the upper ends 50 of the arms or posts 27 and serve to assist in retaining these posts in the proper position and also serve to provide the upper edges of the walls with rounded edges. The 55 upper edge portions of the end walls are also bent over to provide these walls with rounded edges but in the preferred form the end walls have their upper edge portions turned inwardly and downwardly instead of outwardly.

The axles 33 extend beneath the body intermediate its length and in spaced relation to each other and have their end portions rotatably mounted in bearings or journal 60 boxes 34 which are secured to the interme-

diate section of the flooring or bottom of the car body in the usual manner. The end portions of the axles extend outwardly beyond the side edges of the intermediate floor section but terminate short of the vertical plane of the side walls. The wheels 35 are mounted upon these extended end portions of the axles and these wheels have their upper portions extending into the end portions of the pockets 20. Brake shoes 36 are provided between the wheels at each side of the car and these shoes are suspended by hanger strips 37 which are pivotally connected with bracket strips 38. These bracket strips 38 are disposed intermediate the length of the pocket 20 in spaced relation to each other and are secured by rivets or other suitable fasteners. Links 39 are pivotally connected with the brake shoes and extend towards each other with their adjacent ends pivotally connected with the upper end of a strip 40 which is pivotally connected with the outer end portion of the arm 41 of the operating shaft 42. One of these shafts 42 will be provided at each side 90 of the car and these shafts extend beyond the end wall and are provided with upwardly extending lever arms 43 which are connected with the operating lever 44 by links 45. The links 45 are connected with the lever 44 above and below the pivot point 46 of the lever 44 and therefore when the operating lever is moved the levers 43 of the two shafts will both be swung either inwardly or outwardly at the same time. This will cause 95 both of the shafts to be rotated to either apply or release the brakes.

The Z-bar side sills 21 which are shown and described herein may extend substantially the length of the car body and when they rest on the journal boxes 34 serve as additional supporting means for such car body. An additional support is provided by the flange connection of the side floor sections 16 and 19 to the side wall of the car body and the connection of the yoke members or belts 26 as best illustrated in Figures 4 and 5.

It will therefore be seen that the car body is so constructed that the wheels and the brake structure between the wheels at each side of the car may be mounted below the bottom or flooring of the car body without the wheels or brake structure extending beyond the sides of the car body.

A feature of the invention comprises the floor portions formed as illustrated in Fig. 3 in which four metallic corner floor sheets 16 are provided overlapping the upper flanges of the Z-shaped side sills as shown in Figs. 4 and 5, and the twin wheel hoods or intermediate longitudinal metallic floor portions 19 are each formed of a single sheet of metal lapping the corner sheet 16 and riveted thereto.

Such intermediate floor portions 19 overlap the sills 21 and wood floor portions and are bent upwardly as illustrated in Figs. 1, 3 and 4 to form twin wheel hoods, that is, 6 hoods each capable of covering and partly enclosing a pair of supporting wheels and brake rigging hereinbefore described, which 10 brake rigging is positioned within these twin wheel hoods and relatively between the side walls of the car, between the wheels at each side, thus utilizing all of the space covered by the twin wheel hoods to the best advantage.

What is claimed is:

15 1. In a car structure, a body having a bottom, side walls, and end walls, said bottom comprising an intermediate section formed of longitudinally extending floor boards and side sections formed of metallic plates having their inner side portions overlapping the intermediate section and their outer side portions connected with said side walls, Z-bars extending along the side faces of the intermediate section and having their 25 upper flanges secured to the under faces of the side sections and their lower flanges extending beneath the intermediate section, and fasteners securing the side sections and lower flanges of said Z-bars to the intermediate section.

2. In a car structure, a body having a bottom, side walls, and end walls, said bottom comprising an intermediate section and side sections, the side sections being formed of metallic plates having their outer side portions connected with said side walls and their inner side portions overlapping the intermediate section, Z-bars extending along the sides of the intermediate section and having their upper flanges secured to the under faces of the side sections and their lower flanges extending beneath the side portions of the intermediate section and fasteners securing said lower flanges and the overlapped inner side portions of said side sections to said intermediate section.

3. In a car structure, a body having a bottom, side walls, and end walls, said bottom comprising an intermediate floor section formed of planks extending beyond the car body to form bumpers and side sections, the side sections being formed of metallic plates having their outer side portions secured to said side walls and their inner side portions overlapping said intermediate section, side sills extending along the sides of said intermediate section and beneath the side and intermediate sections, fasteners securing said side sills in place and the side sills and side sections to the side portions of the intermediate section, and yokes extending transversely beneath said bottom and secured to the sections thereof and having upstanding arms constituting wall posts secured against the outer faces of said side walls.

4. In a car structure, a body having a bottom, side walls, and end walls, said bottom comprising an intermediate floor section formed of planks extending beyond the car body to form bumpers and side sections, the 70 side sections being formed of metallic plates having their outer side portions secured to said side walls and their inner side portions overlapping said intermediate section, side sills extending along the sides of said intermediate section and beneath the side and intermediate sections, and bracing the bottom at the connection of the side sections with the intermediate section, and U-shaped yokes extending transversely beneath the bottom 75 and secured to the side and intermediate sections thereof and having their arms extending upwardly and constituting wall posts secured against the outer faces of said side walls.

5. In a car structure, a body having a bottom, side walls and end walls, said bottom comprising an intermediate section formed of longitudinally extending floor boards and side sections formed of metallic plates having their inner side portions overlapping floor boards of the intermediate section and their outer side portions provided with upstanding flanges secured to the side walls, Z-bars extending along the sides of the intermediate section and having their lower flanges extending beneath the intermediate section and their upper flanges extending beneath the side sections, fasteners securing the Z-bars to the side sections and other fasteners securing the Z-bars and inner side portions of the side sections to said intermediate section, and yokes extending beneath said bottom and secured to the intermediate and side sections thereof and having upstanding arms constituting posts secured against the outer faces of said side walls.

6. In a car structure, a body having a bottom, side walls and end walls, said bottom comprising an intermediate section and side sections, the side sections being formed of metallic plates having their outer side portions secured to said side walls and their inner side portions secured to the intermediate section, the side sections intermediate the length of said body being bent upwardly to provide pockets extending longitudinally of the body and open at their lower and outer sides for receiving wheels and brake mechanism for the wheels.

7. In a car structure, a body having a bottom, side walls and end walls, said bottom comprising an intermediate section and side sections, the side sections being formed of metallic plates having their outer side portions secured to said side walls and their inner side portions secured to the intermediate section, the side sections intermediate the length of said body being bent upwardly to provide pockets extending lon-

gitudinally of the body and open at their lower and outer sides, axles extending transversely beneath the body with their end portions disposed beneath end portions of the pockets, wheels upon said axles extending upwardly into said pockets, and brake means disposed intermediate the length of each pocket and between the wheels.

8. In a car structure, a body having a bottom, side walls, and end walls, said bottom having its side portions provided with upwardly disposed portions positioned intermediate its length and providing the body with side pockets open at their lower and outer sides, axles extending transversely beneath the body with their ends positioned beneath said pockets, wheels upon said axles and extending into said pockets, and brake means between the wheels and suspended from hangers disposed intermediate the ends of the pockets.

9. A mine car comprising side walls, a central floor section, side floor sections lapping the central floor section near each end of the car at each side of the latter, and twin wheel hoods connecting said side floor sections at each side of the car and having relatively horizontal flanges lapping said central floor section and relatively vertical flanges lapping and secured to said side walls.

10. A mine car comprising side walls, a central floor section, side floor sections in contact with the central floor section near each end of the car, and twin wheel hoods extending longitudinally of the car and connecting said side floor sections at each side of the car.

11. In a mine car, a plate girder side wall of greater depth at its ends than near its middle, floor sections flanged upwardly lapping and being connected with end portions of said side wall and a wheel hood adapted to cover a plurality of wheels extending to a higher plane than the floor sections and lapping the floor sections and the middle portion of said side wall.

12. In a mine car, Z-shaped longitudinal members, a central wood floor in the plane thereof, side floor sections lapping said Z-members, an upwardly extending wheel hood lapping said side floor sections and said central wood floor section and a side wall lapping the wheel hood and side floor sections.

13. In a mine car, a central wood floor section, metallic side floor sections having vertical flanges, a side wall riveted to said metallic floor sections and a plural wheel hood extending to a plane relatively higher than said wood floor and having a flange secured to the wood floor and another flange riveted to the side wall.

14. In a mine car, a central wood floor and a plurality of upwardly flanged side

floor sections at each side of the car, and intermediate arched twin wheel hoods at each side of the car and each lapping the floor sections of one side of the car and being connected thereto.

15. A mine car comprising axles, journal boxes, wheels, an intermediate floor section, upwardly flanged side floor sections, wheel housings each covering a plurality of wheels and having upwardly extending flanges, and side walls lapping and being connected with the flanges of said floor sections and wheel housings.

16. In combination, wheels, axles, journal boxes, a central floor section intersecting the plane of the upper part of said wheels, a Z-shaped longitudinally extending member resting on said journal boxes under and at the sides of said central floor section, side walls cut away in the zone of said wheels and having flanged connection with side portions of the floor.

17. In a mine car, a central floor section, side sills lapping said floor section, side floor sheets lapping said central floor section and said sills and secured to both and side walls having flanged connection with said side floor sheets, said side walls being of reduced depth intermediate their ends.

18. In a mine car, Z-shaped side sills, a wood floor resting on the lower flange of said sills and extending longitudinally beyond the car body to form bumpers, side floor sections resting on said sills and curved upwardly near the middle of the car body to clear car wheels and side walls cut away in the zone of car wheels and having flanged connection with said side floor sections.

19. In a mine car, wheels, axles, journal boxes, a central floor between said wheels, a side floor in a plane below the tops of said wheels, and twin wheel hoods extending outwardly from said central floor and forming hoods for wheels and parts of a brake rigging.

20. In a mine car, wheels, journal boxes, flanged side sills resting on the latter, a wood floor overlapping flanges of said sills and extending between parts of said journal boxes, side floor portions extending over said wood floor and means connecting the side floor, wood floor and sills.

21. In a mine car, wheels, journal boxes, flanged side sills resting on the latter, a central floor section extending between webs of and overlapping flanges of said sills and side floor sections connected directly to said floor and sills.

22. In a mine car, wheels, axles, journal boxes on said axles rising to a plane considerably above the axle, side sills resting on parts of said journal boxes and between other parts thereof, a central floor above and intermediate parts of said sills, side

floors in a plane below tread faces of said wheels and wheel hoods over the tops of said wheels.

23. In a car of the class described, a central floor section, four side floor sections, one extending to each corner of the car, and twin wheel hood sections each being of an area sufficient to cover a plurality of wheels and each being connected with two of said side

10 floor sections of one side of the car.

24. In a mine car, a central floor portion, flanged side sills adapted to rest on journal boxes, side floor portions riveted to the top flanges of said sills and twin wheel hoods
15 lapping and being riveted to said sills, riveted to said side floor portions and being arched over the zone of a plurality of wheels at each side of the car.

25. A railway car having an opening in its adjacent side and bottom walls which 20 extends a substantial distance in a longitudinal direction, and a car wheel hood entirely closing the opening and being of such length as to overlie a plurality of car wheels journaled therebelow.

26. As an article of manufacture, a sheet metal car wheel hood of a length to overlie a plurality of longitudinally alined car wheels, and having attaching flanges at its edges whereby the hood may be secured to 30 the bottom and adjacent side wall of a car to overlie such wheels.

In witness whereof we have hereunto set our hands.

WARREN V. JOHNSON.
ROBERT C. KEPNER.
